UNITED STATES PATENT OFFICE

WILLIAM J. YOUNG, OF LYNN, MASSACHUSETTS, ASSIGNOR TO W. J. YOUNG MANUFACTORY COMPANY, OF LYNN, MASSACHUSETTS, A CORPORATION OF MASSACHUSETTS

HEEL-NAILING MACHINE

Application filed March 10, 1927. Serial No. 174,145.

This invention relates to machines for attaching heels to shoes by driving nails through the heel seat from the inside of the shoe into the heel. This mode of attachment is used for securing wood heels, although it is not necessarily limited as to the character, class or construction of heel with which it may be used.

Machines of this type are arranged to drive the nails upwardly and are provided with a block having guideways for the nails and nail drivers, over which the heel part of the shoe is placed in an inverted position; and they also have rests or stops which are brought down on the tread surface, or both the tread surface and the back of the heel, after the shoe has been thus placed, to hold the heel against the thrust of the nails being driven. In the machines of this character heretofore produced, the stop or rest is thus brought down by the machine operator through the agency of a treadle on which he steps, and is held against the thrust of the driving operation by his weight applied to the treadle. Thus the force with which the nail driving action is opposed is uncertain and variable, being dependent on the weight of the operator; and when the machine operator is a small and light man, is often insufficient to effect a tight and firm attachment of the heel to the shoe. In any event, even if the operator is a heavy man, his weight applies only a yielding force to the stop, so that under the best conditions the nails lack the depth of penetration into the heel which would be secured if they were driven against a rigid and unyielding stop.

In addition to this effect upon the work, the operation of the prior machines has a disagreeable, and sometimes harmful effect on the operator himself, due to the jolt which is transmitted by the driving blow to the treadle on which he stands. The repeated shocks thus administered at frequent intervals throughout the working day have a seriously fatiguing effect on the operator.

One of the objects of this invention has been to overcome and remove the deficiencies and objectionable qualities of the previous machines, above referred to; and this object

is accomplished by providing means for holding the stop or abutment rigidly against the heel in position to be nailed, and transferring the reaction of the stop to the rigid framework of the machine and away from the treadle on which the operator stands.

Another object is to facilitate adjusting or changing the machine to drive nails in different numbers and patterns, as is required for shoes of different sizes and having different styles of heel. This last object is accomplished by providing a nail block and an associated set of nail drivers in a unit assemblage capable of application as such unit to the machine, removal therefrom, and substitution of other units having different characteristics of size and number and pattern of nail guideways and drivers.

In the following specification and in the drawings accompanying the same, I have described and illustrated a heel nailing machine of the type above referred to containing the preferred embodiments of the present invention.

Fig. 1 of the drawings is a front elevation of such a machine, partly broken away in the lower portion to reduce its height;

Fig. 2 is a cross section or sectional plan on line 2—2 of Fig. 1;

Fig. 3 is a detail section on line 3—3 of Fig. 2;

Fig. 4 is a perspective view illustrating my new nail block and driver assemblage and the part of the machine in which the same is mounted;

Fig. 5 is a vertical central section of the machine taken on line 5—5 of Fig. 1;

Fig. 6 is a detail sectional view showing the heel stop controlling cam in position for pressing the stop against the heel of a shoe into which nails are to be driven.

Like reference characters designate the same parts wherever they occur in all the figures.

A massive frame supports the working parts. In the design here shown, the frame is a single integral casting of hollow semi-conical form with side portions 1, 2, and a rear portion 3, and a bottom web 4. The side portions at the base are extended for

wardly as webs 5 and 6, containing bearings to support a shaft 7, to which a nail driver cam 8 is secured, and a drive shaft 9 geared to shaft 7 by gear wheels 10 and 11, and having a pulley 12 receiving a driving belt 13. The side portions 1 and 2 are upwardly extended at the top of the frame to form lugs 14 and 15 having inwardly directed alined bearing sleeves 16 and 17, in which a shaft 18 has its bearings.

A guide block 19 is mounted across the front of the frame, having webs 20 which are bolted to the side members. A second guide block 22 is similarly mounted and secured below the guide block 19. These guide blocks have passages or guideways vertically alined with one another in a line which crosses the axis of shaft 7. The passage in block 22 contains a slide or plunger 23, and that in the guide 19 contains a slidable block or head 24 adjustably secured to the plunger 23, by being screwed upon the threaded end part of said plunger and engaged by a lock nut 25 similarly screwed upon the plunger. The lower end of plunger 23 carries a trundle roll 26 engaging the cam 8.

In the upper part of guide block 19 is a recess 27 extending from front to rear and open at the front. The block or head projects at its upper end into said recess and has a flange 28 overlying the bottom thereof to arrest it at the lower limit of its reciprocating movement. The sides of the guide block flanking the recess have guideways 29 formed in part by removable top plates 30, which guideways receive flanges 31 at opposite sides of the base part of a block 32. Said block is at the same time a jack for supporting the shoe while its heel is being nailed on, a receiver for the nails to be driven, and a guide for the nail drivers.

For convenient designation in this specification, it will be generally referred to as a nail block. Said nail block contains longitudinal passages 33 conforming in number and arrangement, or pattern, to the nails required for attaching a heel of a given style to a shoe of a given size. Nail drivers or driving rods 34 of well known character occupy these guideways and are adapted to move freely endwise therein. Said drivers project from the lower end of the block and are all secured to a plate 35, conveniently by being screwed into tapped holes in the plate in locations corresponding to the pattern of the passages 33. Springs 36 surround the drivers, or a sufficient number of them, and are confined between the plate 35 and the block, preferably extending somewhat into the block in sockets formed as enlargements of the lower ends of the passages 33, in order that the springs may be long enough to escape being over-strained when compressed and to permit approach of the plate 35 all the way to the end of the nail block if necessary. These

springs assure retraction of the drivers after they have been advanced to drive nails. Complete withdrawal of the nail drivers from the nail passages, when the nail block is removed from the machine, is prevented by a stop screw 37 passing through the plate 35 into the block and having a head somewhat underlying the plate. Instead of having separate springs surrounding the nail drivers, the same effect may be secured in an equivalent way by providing a single spring surrounding the stop screw 37, or in other ways. The nail block is loaded, prior to nailing the heel on a shoe, by dropping the nails head first in the upper ends of the passages 33 when the drivers are retracted, as shown in Fig. 5. The shoe, with its heel temporarily attached by adhesive, or otherwise, is placed on the nail block in an inverted position, as shown by broken lines in Fig. 5. The exterior of the block, which is shaped to conform to the interior of the heel part and counter of the shoe, enables it to serve as a jack in correctly positioning the shoe to receive the nails.

Different nail blocks or jacks suitably shaped for shoes of different sizes, and having nail passages in various numbers and variously patterned according to the size of shoe and style of heel, may be substituted for one another. Such substitution is made possible by the construction of the guide piece 19 with its recess 27 and guideways 29, and the nail block with its flanges 31 complementary to said guideways. When the nail block is removed, the drivers and the plate 35 come with it, such block and drivers constituting a self contained unit capable of being applied and removed and, when removed from the machine, remaining as such a unit. The stop screw 37 not only prevents accidental removal of the drivers from the nail block, but it also limits the separation of the plate 35 from the nail block to that degree which permits it to be slipped in and out of the space over the driving head 28 when the latter is fully retracted. A pin or bolt 38 passing into one of the guideways from the outside of the guide block 19, and into a hole 39 in the adjacent base of the nail block secures the latter in place. Such bolt or locking pin is carried by a flexible spring 40 which normally holds the bolt in locking position, but can be flexed, as shown in Fig. 4, to withdraw the bolt.

An abutment stop or rest is provided to bear on the heel and sustain it against the thrust and blow applied in driving the nail. Such stop or rest comprises a tread abutment 41 arranged to bear on the tread end or face of the heel, and a cooperating back stop or rest 42 is provided to engage the rear of the heel when the heel is so high and its tread so inclined to the direction in which force is applied by the nail drivers as to tend to wedge the shoe to the rear. These stops or

rests are adjustably mounted in or on a holder 43 which in turn is adjustably mounted between arms 44 and 45 projecting forwardly from a slide 46 which occupies vertical guideways 47 and 48 in the side members of the main or base frame. The stop 41 is a block having a wing 49 connected pivotally by a clamp screw 50 to a lug 51 on a bar or plunger 52, which enters a socket from the under side of the block 42, is guided in said socket by a ring 53 secured in the mouth of the socket and by a head 54 on its own upper end, and is supported by a spring 55 surrounding it and confined between the ring 53 and head 54. A screw 56 is threaded through the upper part of the holder 43 into said socket and bears on the end of the bar 52, serving to adjust the stop 41 for heels of different heights. A lock nut 57 secures the adjustments. The cooperating stop or rest 42 is recessed with flaring sides adapted to embrace partially the rear part of a heel of any size and has a shank 58 connected by a pivot clamp screw 59 with a slotted bar 60 which 25 in turn is attached to a lug 61 of the holder by a clamp screw 62. This clamp screw passes through the slot in the bar 60 and permits the latter to be adjusted both lengthwise and angularly. The lug 61 is so formed 30 and disposed as to bring the middle part of the stop 41 in the longitudinal medial plane of the nail block or jack 32. The capacity for adjustment above described of the stops 41 and 42 enables them to be set for heels of 35 any height and inclination. Both are positioned according to the location of the heel by moving the holder 43 to the front or rear, for which purpose said holder is provided with ribs 63 occupying guideways 64 on the 40 inner sides of the webs or arms 44 and 45, and an adjusting screw 65 is entered into a tapped hole in the forward side of the holder and its shank laid in a notch in a plate 66 bridging across and secured to the outer ends 45 of said webs or arms, said shank having collars 67 to prevent end movement. The webs or arms 44 and 45 contain a sufficiency of material suitably disposed to render them amply rigid for the purposes of their use.

50 The slide 46 is normally raised by a spring 68 connected at one end to a hook 69 on the slide, and anchored at the other end to a hook 70 on the base frame. At its upper end it carries an anti-friction roll 71 bearing on a cam 72 secured to the shaft 18. An arm 73 is secured to the same shaft and is connected by a link 74 to a treadle 75 pivoted at 76 to the base. A spring 77 connected to the treadle and anchored on the base frame normally raises the treadle to the limit permitted by a stop 78, thereby placing the cam 72 in the position shown in Fig. 5. Arm 73 has suitable length in proportion to the throw of the treadle, such that it is well removed from 65 its dead point, considered as a crank of the

shaft 18, when in either possible extreme position, wherefore it will oppose no appreciable resistance to depression of the treadle by the operator's foot or to lifting of the treadle by the spring 77.

The axis of the cam 72 is substantially vertically over the center of the roll 71; or, in other words, is substantially in the line in which slide 46 is constrained to move by its guideways. In other respects, the cam is so 70 designed that its highest part (part of longest radius) is directly over and in contact with the roll 71 when the treadle is fully depressed. Thus the line in which the reaction of the slide is exerted is then normal to the 75 surface of the cam and passes through its center of rotation. This form and arrangement of the cam is of great importance, as it enables the cam to take the entire thrust or reaction applied to the heel stops or rests 80 when the nails are driven, and to transmit this reaction directly to the rigid frame of the machine, without any lifting effect on the treadle. Thus the first named and principal object of my invention is accomplished. The 85 resistance opposed by the abutment stops to the nail driving force is not in any degree dependent upon the weight or pressure applied by the operator to the treadle, and the operator is relieved of jolting due to the impact 90 of the nail driving mechanism.

The foregoing conditions that the axis of the cam is directly above the stop carrying slide, and that the highest point of the cam is in contact with the slide when the latter is 100 depressed, are subject to some modification and variation. These conditions may be exactly or substantially so, or the cam axis may be slightly forward of the engaging point of the slide, sufficiently to bring the point of 105 longest radius of the cam forward of the highest point of the slide, or the cam may be otherwise so formed as to obtain the same effect. In other words, I may so form or locate the cam that the full depression of the 110 treadle carries its highest point slightly beyond the point at which it engages the slide, although not enough so to permit rise of the heel stops and relaxation of the pressure 115 exerted by them upon the heel. The result of thus carrying the cam further onward is to remove any possibility of the up thrust of the cam exerting any lifting effect on the treadle, but rather to cause down thrust on the treadle.

The operation of the machine may be readily understood from the foregoing description of construction and relation of the parts, without further explanation. It may be mentioned, however, that the driver operating cam 8 is driven with sufficient speed to strike substantially a hammer blow on the nail drivers, and that in place of the cam, other driver impelling means well known in the art of nail driving machines may be used.

It is also to be understood that a clutch or other starting and stopping device of a well known character is, or may be, applied to the cam shaft 7 or to the driving shaft 9 to cause the nail driving mechanism to remain normally at rest and to be operated only when the treadle 75 is depressed, or some other control device is operated. But as the type of such starting and stopping mechanisms which I prefer to use in this machine is old and involves no invention of mine, I have not illustrated it herein.

It may be further understood that the various parts of the machine are, or may be, made of structural materials usual in the construction of shoe machinery, machine tools, etc., according to the judgment of the machine designer or builder.

What I claim and desire to secure by Letters Patent is:

1. A machine for attaching heels to shoes comprising nail driving mechanism, a rest for sustaining a heel against the force applied by said nail driving mechanism, a slide carrying said rest and movable to place the rest in and out of its sustaining position, a cam for placing and holding the slide and rest in said sustaining position, and operator-actuated means for so moving said cam, the cam having means for transmitting to the machine structure substantially all of the reaction of the rest.
2. A machine for attaching heels to shoes comprising nail driving mechanism, a rest for sustaining a heel against the force applied by said nail driving mechanism, a slide carrying said rest and movable to place the rest in and out of its sustaining position, a cam for placing and holding the slide and rest in said sustaining position, and operator-actuated means for so moving said cam, the cam being arranged with its pivot point and point of engagement with the slide substantially in line with the direction of movement of that part of the slide which engages the cam, and with its engaging surface extending squarely across said line of movement.
3. A machine for attaching heels to shoes comprising a nail driving mechanism, a rest for sustaining the heel against the force applied thereto by the said mechanism, movable in a given path to carry the rest into and out of its sustaining position, a cam engaging a point on said slide, mounted to turn about an axis lying approximately in the line of movement of said point, and operator-actuated means for turning said cam to advance the slide into said sustaining position, the cam being thereby interposed in the direct line of reaction of the slide and its surface of greatest radius being then substantially normal to such line, thus relieving the operator-actuated means of substantially all of such reaction.
4. A heel nailing machine comprising a

frame structure, a guide member secured to said structure having a recess in its upper part with transverse guideways, and a passage in its lower part opening into said recess, a driver impelling member contained and movable in said passage, means for reciprocating said impelling member, a nail block having flanges occupying said guideways, normally holding the same removably in the upper end of said recess and over the before named passage, said block having passageways adapted to receive nails and nail drivers, nail drivers occupying said passageways and protruding from the lower end of the block, a plate with which the protruding ends of said drivers are all engaged, and means for connecting said plate to the nail block and limiting its distance from the bottom of the latter, while permitting its movement toward said bottom.

In testimony whereof I have affixed my signature.

WILLIAM J. YOUNG.
